PILLOW

Wanda Chandler Morse and Wayne T. Morse, both of 515 S. 13th, Apt. 13B, Las Vegas, Nev. 89104

Filed July 27, 1965, Ser. No. 86,312

Term of patent 14 years

(Cl. D3—9)

FIG. 1

FIG. 2

FIG. 3

The rear view of FIG. 1 would appear substantially as the front view.

We claim:

The ornamental design for pillow, as shown and described.
